UNITED STATES PATENT OFFICE.

WILLIAM NEWLIN, OF ATTICA, ASSIGNOR OF ONE-HALF TO JAMES S. WARWICK, OF LAFAYETTE, INDIANA.

WHEEL-PLOW.

SPECIFICATION forming part of Letters Patent No. 316,053, dated April 21, 1885.

Application filed January 13, 1885. (No model.)

To all whom it may concern:

Be it known that I, WILLIAM NEWLIN, of Attica, in the county of Fountain and State of Indiana, have invented certain new and 5 useful Improvements in Wheel-Plows; and I do hereby declare the following to be a full, clear, and exact description of the invention, such as will enable others skilled in the art to which it appertains to make and use the same.

10 My invention relates to an improvement in wheel-plows, the object of the same being to provide improved means for attaching the rear axle to the frame in such manner that the rear land-wheel can be so adjusted that when 15 the furrow-wheel is in a furrow the plow will occupy a level position instead of being tilted to one side. A further object is to provide improved means for elevating and lowering the plowshare. A further object is to provide 20 improved devices for securing the forward furrow-wheel to the plow in such manner that when the furrow-wheel is in the furrow the front furrow-wheel will be enabled to run smoothly upon the bottom of the furrow 25 without tilting the plow. A further object is to provide a plow of the above character which shall be simple and economical in construction and durable and efficient in use; and with these ends in view my invention consists 30 in certain features of construction and combinations of parts, as will be hereinafter fully described, and pointed out in the claims.

In the accompanying drawings, Figure 1 is a view in perspective of the plow in working 35 position, and Fig. 2 is a view thereof in side elevation.

A represents the plow-beam provided with the downwardly and forwardly projecting end B, the rear end thereof being curved down- 40 wardly and provided with the foot C, to which is rigidly secured the landside D. The upper rear end of the beam is provided with the rearwardly-projecting nose E, which can be formed therewith or separately and se- 45 cured thereto in any desired manner. The rear axle, F, is connected with the beam by means of the bars G, forming the frame, which are journaled to the axle on each side of the furrow-wheel H. The rear portion of the bars 50 extend downwardly from the axle, and are curved forwardly and upwardly and inwardly

at their extreme ends, embracing the sides of the beam A, to which they are pivotally secured by means of the pivot-bolt I. The extreme ends of the said bars are connected together by means of the yoke J, which encircles the top of the beam A, and by means of which the beam is prevented from riding upwardly out of position. The foot-rest K is secured on the bars G by means of a suitable 55 bolt, L, the head of which rests against the lower edges of the bars. The seat-support M is formed integral with the foot-rest and extends upwardly and backwardly, terminating over the center of the furrow-wheel H. If 60 desired, the seat-support may be formed separate and secured in any convenient manner. The inner side of the foot-rest K is provided on its bottom with the sleeve N, in which is journaled the foot-actuated lever O. The for- 65 ward part of the lever is bent at right angles with the beam, and is adapted to bear against the under side of the nose E, the object of the lever being to elevate the heel of the plow- 70 share when desired by the pressure of the foot 75 of the operator.

Adjoining the wheel H, and rigidly secured to the bar G, is the sleeve P, to which is rigidly secured the sector-bar Q, to one side of which is rigidly secured on the axle F the lever R, provided with the spring-actuated dog S, by means of which the same is held in fixed adjustment. The axle F is cranked, as shown—that is, downwardly from about the center, and then outwardly a sufficient distance to receive the land-wheel F', and is provided with the brace T, which is journaled thereon, the forward end of the brace being pivoted to the beam A. Thus it will be seen that by providing the cranked axle, lever, and sector- 80 bar, effective means are provided whereby the landside of the frame can be sufficiently elevated or lowered by throwing the lever back or forward to prevent the plow from tilting sidewise when the wheel F is in the furrow. 85 90 95

To the forward end of the beam A is rigidly secured the sleeve U, a portion of which is cut away, forming the recess V, on one side of which is rigidly secured the sector-bar W. The arm a is journaled in the said sleeve U, 100 and is provided near its end with the shoulder b, and on the end with the vertical sleeve

c, adapted to receive the upper end of the cranked axle *d*, to the lower end of which is journaled the front furrow-wheel, *e*. To the extreme upper end of the axle *d* is pivoted the tongue *f* in such manner as to permit the tongue to be freely elevated and depressed. The lever *g* is rigidly secured to the arm *a* in the recess *V*, and is provided with the spring-actuated dog *h*, by means of which the lever is held in any desired adjustment. The front furrow-wheel, *e*, can be adjusted as desired by means of the lever *g*—as, for instance, when the furrow-wheel *H* is in the furrow the forward furrow-wheel, *e*, can be elevated to correspond with the rear land-wheel, *F*, and the plow can be thus adjusted so that it will run at all times freely and smoothly.

When it is desired to turn the plow around, the team can be greatly relieved by the operator pressing and holding down the foot-lever *O*, thus elevating the heel of the plow. The lever *R* is then thrown backward and locked by means of the dog *S*. The front end of plow-beam is then elevated by drawing the lever *g* backward. The weight of the operator is then thrown against the locked lever *R*, and the effect will be to elevate the plow, and the same is then conveniently turned, meeting with but slight obstruction.

It will be seen that in the manner of locating the seat the principal weight of the operator is thrown upon the rear furrow-wheel, thus relieving the land-wheel of the weight where the tendency of such weight would be to bury the wheel and produce side draft.

I would have it understood that I do not limit myself to the exact construction shown and described, but hold myself at liberty to make such variations as properly fall within the spirit and scope of my invention.

My device is simple and economical in construction and durable and efficient in use.

Having fully described my invention, what I claim as new, and desire to secure by Letters Patent, is—

1. In a wheel-plow, the combination, with the frame journaled on a cranked axle, the forward end of the frame being joined by a yoke, of a beam pivoted to said frame, and a foot-lever for elevating the rear of said beam, substantially as set forth.

2. In a wheel-plow, the combination, with a cranked axle and a furrow-wheel and a land-wheel journaled thereon, of a frame the rear end of which is journaled to said axle, a plow-

beam pivotally secured to the front end of said frame, a seat secured to the said frame above the furrow-wheel, and a foot-lever journaled to the frame and engaging the plow-beam behind the pivotal connection of said beam and frame.

3. In a wheel-plow, the combination, with the frame, and a foot-rest and seat secured to the forward end thereof, of a beam pivoted to said frame and provided with a rearwardly-projecting nose, and a foot-lever journaled to said foot-rest and adapted to engage said nose, whereby the beam is elevated and lowered, substantially as set forth. 65

4. In a wheel-plow, the combination, with the frame and a beam secured thereto, of a sleeve rigidly secured on the forward end of said beam and a crank-axle, and a furrow-wheel journaled in said sleeve, and devices for elevating and lowering the said furrow-wheel, substantially as set forth. 70

5. In a wheel-plow, the combination, with the frame and a beam pivoted thereto, of a sleeve rigidly secured on said beam, and a crank-axle journaled in said sleeve, and a sector-bar secured thereon, and a lever and dog for locking the axle in any desired position on the shaft, substantially as set forth. 75

6. In a wheel-plow, the combination, with a plow-beam provided with a horizontal sleeve at its front end, of an arm journaled in said sleeve and provided at one end with a vertical bearing, a vertical axle journaled in said bearing and provided at its lower end with a horizontal spindle, a wheel journaled on said spindle, and a tongue pivoted to the upper end of the vertical axle. 85

7. In a wheel-plow, the combination, with a plow-beam provided with a horizontal sleeve at its front end, of an arm journaled in said sleeve and provided at one end with a vertical bearing, a lever and sector for turning and locking the arm in any desired rotary adjustment, a vertical axle journaled in the bearing in said arm and provided at its lower end with a horizontal spindle, a wheel journaled on said spindle, and a tongue pivoted to the upper end of the axle, substantially as set forth. 95

In testimony whereof I have signed this specification in the presence of two subscribing witnesses. 100

WILLIAM NEWLIN.
